[57] CLAIM

The ornamental design for a display advertising unit for storage fixtures or the like, as shown and described.

DESCRIPTION

FIG. 1 is a front elevational view of a display advertising unit for store fixtures or the like showing my new design;

FIG. 2 is a front perspective view thereof;

FIG. 3 is a rear perspective view thereof;

FIG. 4 is a front perspective view thereof, with the side panel removed for ease of illustration; and,

FIG. 5 is a rear perspective view thereof, with the side panel removed for ease of illustration.

FIG. 1

FIG. 2

FIG. 3
